UNITED STATES PATENT OFFICE

SALLY BRYAN, OF DENVER, COLORADO

DESIGN FOR A CONTAINER FOR IMPARTING RADIUM EMANATIONS TO FLUIDS

Application filed February 14, 1929. Serial No. 30,046. Term of patent 14 years.

To all whom it may concern:

Be it known that I, SALLY BRYAN, a citizen of the United States, residing in the city and county of Denver, State of Colorado, have invented a new, original, and ornamental Design for a Container for Imparting Radium Emanations to Fluids, of which the following is a specification, reference being had to the accompanying drawing, forming part thereof.

Figure 1 is an elevational view of a container for imparting radium emanations to fluids, and

Figure 2 is an elevation thereof, turned ninety degrees, showing my new design.

I claim—

The ornamental design for a container for imparting radium emanations to fluids, as shown.

SALLY BRYAN.
